(57) **CLAIM**

I claim the ornamental design for a wall plug housing, as shown and described.

DESCRIPTION

FIG. 1 is a front perspective view of a wall plug housing; FIG. 2 is a rear perspective view of the wall plug housing of FIG. 1;

FIG. 3 is a front view of the wall plug housing of FIG. 1; FIG. 4 is a top view of the wall plug housing of FIG. 1; FIG. 5 is a left side view of the wall plug housing of FIG. 1;

FIG. 6 is a right side view of the wall plug housing of FIG. 1;

FIG. 7 is a rear view of the wall plug housing of FIG. 1; and, FIG. 8 is a bottom view of the wall plug housing of FIG. 1. The broken lines in the drawings illustrate portions of the wall plug housing that form no part of the claimed design.

1 Claim, 4 Drawing Sheets
